UNITED STATES PATENT OFFICE.

FRED E. KLING AND REINHOLD C. KRAUSE, OF YOUNGSTOWN, OHIO.

BELL-OPERATING MECHANISM.

Application filed July 29, 1925. Serial No. 46,770.

This invention relates to blast furnaces and more particularly to blast furnace bell operating mechanism, and has for its object the provision of an improved form of cushioned bell operating mechanism which facilitates the opening and closing of the bell, insures tight closing of the bell and prevents injurious straining of the operating cables and mechanism, and also of the bell mountings and furnace top.

Another object is to provide a blast furnace bell operating mechanism having the novel design, construction and combination of parts hereinafter described and illustrated in the accompanying drawings.

In the drawings—

Figure 1 is a sectional elevation through a blast furnace embodying our invention.

Figure 2 is a detail front elevation of the bell lifting levers and rods.

Figure 3 is an enlarged detail side elevation of one of the bell operating mechanisms of this invention.

Figure 4 is a detail of the forward end of the mechanism of Figure 3, showing the construction of the link used for the small bell operating mechanism.

Figure 5 is a sectional elevation on the line V—V of Figure 3.

Figure 6 is a plan of the forward end of the rack member of the bell operating mechanism.

Figure 7 is a plan showing the large and small bell operating mechanisms.

Figure 8 is a longitudinal sectional elevation through a modified form of bell operating mechanism.

Referring more particularly to the drawings, the letter A designates the blast furnace as a whole which is of usual and well-known construction, consisting of a hearth portion 2, bosh portion 3 and shaft 4. The upper end of the shaft converges and is closed by a lower hopper 5 having its lower end closed by a large bottom bell 6 and its upper end closed by a hood 7. The hood 7 has a centrally arranged opening 8 with which a chute or upper hopper 9 communicates, and the opening 8 is closed by an upper or sealing bell 10. The upper end of the chute 9 is flared outwardly to facilitate the filling of the chute with the material to be charged into the furnace, which material is delivered to the chute by a well known

form of skip-hoist shown at 12 operated on a skip-hoist bridge 14.

The bottom bell 6 is provided with a centrally connected operating rod 15 which extends upwardly through a tubular operating rod 16 centrally connected to the upper or sealing bell 10.

The upper ends of the rods 15 and 16 are connected, respectively, by cables 17 and 18 to the quadrant portions 19 and 20 of rocking levers 21 and 22, which are pivoted as at 23 and 24, respectively, to suitable supports extending upwardly from the top platform 25 of the furnace or skip bridge.

The above arrangement of bells and bell operating levers is common and well known in the art and will not be further described. 70

This invention is directed primarily to a novel means for operating the levers 21 and 22, which consists of a pair of mechanisms B and C mounted on guideways 27 and 28 arranged side by side on top of the skip-hoist bridge 14. The mechanisms B and C are of duplicate construction except for the connecting link to which the operating cables are attached. Therefore, the same reference numerals will be applied to the duplicate parts of both mechanisms.

The mechanisms B and C comprise a wheeled carriage member 30 adapted to move longitudinally on the guideways 27 and 28 and having a centrally arranged guideway 31 in which is slidably mounted a rack member 32. A motor 33 is mounted on the carriage 30 and is connected through suitable reducing gearing, to be described, with a rack pinion 34 mounted on a shaft 35 journaled in bearings 36. The pinion 34 is in mesh with the rack 32 and is adapted to be rotated to reciprocate said rack when the motor is operated. A suitable roller 37 is mounted on a shaft 38 adjacent the forward end of the carriage and directly under the pinion 34 to form a movable support for the rack. 90

The motor 33 has its armature shaft provided with a pinion 39 which is in mesh with a gear 40 on a shaft 41, which shaft also carries a pinion 42 which is in mesh with a gear 43 on a shaft 43^a carrying a pinion 44 which meshes with a gear 44^a on the shaft 35 carrying the rack pinion 34. From the above it will be readily appreciated that the motor 33 will exert consider- 100
105

able power on the rack pinion to reciprocate the rack.

The lower end of the guideways 27 and 28 terminate in a stop abutment 45.

A suitable cushion plunger or bumper 46 is slidably mounted in the carriage 30 and is normally held in extended position by coil springs 47 which are compressed when the carriage is in its lowermost position so that the plunger 46 engages the abutment 45.

A rigid spring support 48 is mounted at the rear end of the carriage 30 and extends through a suitable opening in the abutment 45 and has a plurality of coil springs 49 mounted thereon and held in position by a bearing washer 50 and nut 51 so that when the carriage 30 moves upwardly on the guideways the springs 49 will be compressed between the abutment 45 and the washer 50 and thereby tend to resist the upward travel of the carriage. The spring support 48, springs 49 and associated parts serve to counter-balance the bell load, and may be omitted when the bell load is less than the weight of the operating mechanisms B and C.

A suitable guide and support 53 is mounted forward of the guideways 27 and 28 and serves as a track on which suitable supporting wheels 54 and 55 on the forward end of the rack 32 travel and support the forward end of the rack.

The forward end of the rack 32 is of U-shaped formation with each of the legs 56 apertured to form bearings for a shaft 57 carrying the wheels 54 and 55 and forming a pivotal mounting for a link 58 between the legs 56.

The link 58 for mechanism C which is connected to the operating lever for the upper or small bell has its forward end apertured to receive the shank of a clevis rod 59 which is adjustable by means of nuts 60. The rod 59 carries a sheave 61 between its clevises and a cable 62 has one end secured around a sheave 61 and its other end secured around a sheave 63 on the operating lever 22 of the small upper bell.

The link 58 for the mechanism B which is connected to the operating lever 22 for the lower or large bell has its forward end formed T-shaped and has its head portion apertured adjacent each end for the reception of a pair of clevis rods 64 and 65 which are adjustably locked in position by nuts 66. The rods 64 and 65 carry sheaves 67 and 68, respectively, between their clevises and a cable 69 has one end secured around the sheave 67 and is trained over a sheave 71 mounted on the free end of the operating rod 22 for the large or lower bell, and has its other end secured around the sheave 68.

In operation, when it is desired to lower either of the bells, assuming that the operat-

ing mechanisms are in their closed position, with the racks 32 retracted, the motor 33 will be energized to rotate the pinion in a clockwise direction, thus allowing the mechanisms B or C to travel downward until springs 47 are compressed sufficiently to balance the downward forces. The motor continuing to rotate after the mechanism B or C has come to rest, will cause the rack to travel upwards and allow the bell to lower. The rack in its highest position actuates an electric limit switch (not shown) which stops the motor. When it is desired to close an open bell, the rotation of the motor 33 will be reversed and the pinion 39 rotated in a counter-clockwise direction to retract the rack 32.

When the bells are seated, the operation of the motor is continued for a short interval to permit the carriage to move upward along its guideway and be suspended by the cables connecting it with the bell operating mechanism, thus the entire weight of the carriage and its associated mechanism serves to insure positive seating of the bell and prevent undue strain in the motor, gears, rack, ropes, bell levers and rods. This strain can not exceed the weight of mechanism C, or the weight of mechanism B plus the tension of springs 49, which compress during the upward movement of mechanism B. Another object of lifting the mechanism is to operate an electric limit switch to stop the motor. The carriage being free to move will be accelerated in its upward movement by the tension of the springs 47 against the bumper 46, thus preventing shock to the cables and operating mechanism when starting to lift the mechanism.

It will be understood, however, that in some instances the mechanisms B and C may be of sufficient weight to insure the closing of the bells without the aid of the springs 49, or that counterweights may be used instead of the springs 49, if desired.

In Figure 8 we have shown a slightly modified form of the operating mechanisms B and C, in which a screw rod 80 is substituted for the rack 32 and a nut 81 is mounted on the rod and secured against longitudinal movement in the carriage 30. The nut 81 is provided with a ring gear portion 82 which meshes with a pinion 83 on the armature shaft of a motor 33 mounted on the carriage.

This modified construction of operating mechanism is simpler than the preferred form due to the fact that the reducing gearing between the motor and rack is eliminated. However, the preferred form is the most satisfactory for the heavy duty to which it is subjected in blast furnace operation.

The operation of the modified form is substantially the same as the preferred form,

except that the screw rod 80 is reciprocated instead of the rack 32.

While we have shown the various operating mechanisms mounted to travel on an inclined track it will be understood that they may just as readily be mounted to travel in vertical guideways, if desired. It will also be understood that while we have shown and described certain preferred embodiments of our invention we do not wish to be limited to such constructions, since various modifications embodying the principles of our invention may readily be made without departing from the scope of our invention as defined in the appended claims.

We claim—

1. In a blast furnace having at least one closing bell at its upper end, a guideway extending upwardly alongside said furnace, a carriage movable along said guideway, an operating lever for said bell, means connected to said lever and said carriage adapted to rock said lever to close said bell and to move said carriage upwardly along said guideway when said bell is closed.
2. In a blast furnace having at least one closing bell at its upper end, a guideway extending upwardly alongside said furnace, a carriage movable along said guideway, an operating lever for said bell, operating means carried by said carriage and movable toward and away from said lever and relative to said carriage, a connecting member between said operating means and said lever whereby said lever is rocked to open and close said bell, said operating means, connecting member, lever, and bell being adapted to cooperate whereby continued movement of said operating means after said bell is closed will move said carriage upwardly along said guideway.
3. In a blast furnace having at least one closing bell at its upper end, a guideway extending upwardly alongside said furnace, a carriage movable along said guideway, an operating lever for said bell, means extending between and connected to said carriage and said lever adapted to exert an upward pull on said carriage and to rock said lever to close said bell, said means being adapted to cause an upward movement of said carriage in said guideway after said bell is closed, whereby the weight of said carriage is suspended from said lever.
4. In a blast furnace having at least one closing bell at its upper end, a guideway extending upwardly alongside said furnace, a carriage movable along said guideway, an operating lever for said bell, means extending between and connected to said carriage and said lever adapted to exert an upward pull on said carriage and to rock said lever to close said bell, said means being adapted to cause an upward movement of said carriage in said guideway after said bell is

closed, spring means adapted to be compressed by said upward movement of said carriage so as to add a further pull on the means connecting said carriage and lever whereby seating of said bell is assured. 70

5. In a blast furnace having at least one closing bell at its upper end, a guideway extending upwardly alongside said furnace, a carriage movable along said guideway, an operating lever for said bell, operating 75 means carried by said carriage and movable toward and away from said lever and relative to said carriage, a connecting member between said operating means and said lever whereby said lever is rocked to open and close said bell, said operating means, connecting member, lever, and bell being adapted to cooperate whereby continued movement of said operating means after said bell is closed will move said carriage upwardly 85 along said guideway, and resilient means adapted to facilitate the upward movement of said carriage.

6. In a blast furnace having at least one closing bell at its upper end, a guideway extending upwardly alongside said furnace, a carriage movable along said guideway, an operating lever for said bell, operating 90 means carried by said carriage and movable toward and away from said lever and relative to said carriage, a connecting member between said operating means and said lever whereby said lever is rocked to open and close said bell, said operating means, connecting member, lever, and bell being adapted 95 to cooperate whereby continued movement of said operating means after said bell is closed will move said carriage upwardly along said guideway, and resilient means for retarding the upward movement 100 of said carriage.

7. In a blast furnace having at least one closing bell at its upper end, a guideway extending upwardly alongside said furnace, a carriage movable along said guideway, an 110 operating lever for said bell, operating means carried by said carriage and movable toward and away from said lever and relative to said carriage, a connecting member between said operating means and said lever 115 whereby said lever is rocked to open and close said bell, said operating means, connecting member, lever, and bell being adapted to cooperate whereby continued movement of said operating means after said bell 120 is closed will move said carriage upwardly along said guideway, resilient means for retarding the upward movement of said carriage, and other resilient means for checking the downward movement of said carriage and for facilitating the upward movement of said carriage.

8. In a blast furnace having at least one closing bell at its upper end, a guideway extending upwardly alongside said furnace, a 125

carriage movable along said guideway, an operating lever for said bell, a rack mounted for reciprocation on said carriage, means for reciprocating said rack, and means connecting said rack and said lever whereby said lever will be rocked to open and close said bell when said rack is reciprocated.

9. A blast furnace having a closing bell at its upper end, a guide alongside the fur-

nace, a carriage movable thereon, a member 10 movable relatively to and supported on said carriage, means for driving said member, and means connecting the bell with said member.

In testimony whereof we have hereunto 15 set our hands.

FRED E. KLING.
REINHOLD C. KRAUSE.
